UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

ANTIFRICTION BEARING

Application filed March 12, 1927. Serial No. 174,731.

This invention relates to anti-friction bearings.

An object of the invention is to provide an anti-friction bearing comprising a retainer adapted to be secured to the bolster of a railway car including anti-friction means co-operating with said retainer and adapted to be engaged by the associated bolster and movable thereby to either side of central position with reference to the retainer, together with mechanism for returning the anti-friction means to central position when free from load.

A more particular object of the invention is to provide anti-friction means in the form of a pair of anti-friction rollers connected to move in unison, in conjunction with centrally disposed vertically movable yieldable means which project between the rollers and normally hold the same in central position with reference to the retainer, which yieldable means are adapted to be depressed by engagement with one or the other of the rollers when the rollers are moved in opposite directions whereby said means exerts an upward pressure beneath the roller engaging the same, and to one side of the center of gravity thereof for returning the rollers to their initial starting position, said yieldable means including a follower having a spherical conformation whereby the thrust upon the roller in engagement therewith is at an angle to the vertical movement of said yieldable means.

Other and further objects of the invention will more fully appear from the description and claims hereinafter following.

In the drawings forming part of this specification, Figure 1 is a transverse sectional view taken through the ends of the body and truck bolsters of a railway car, and showing a side elevational view of the invention as applied to the truck bolster. Figure 2 is a top plan view of the anti-friction bearing, showing the same detached

from the truck bolster. And Figure 3 is a transverse vertical sectional view of the anti-friction bearing and truck bolster taken substantially on the line 3—3 of Figure 1.

As shown in the drawings, the anti-friction bearing broadly comprises a base plate A, a retainer B, anti-friction means C, and centering means D.

The base member A is of elongated formation, and is secured to the upper surface of the truck bolster indicated at 10, by means of centrally disposed rivets 11—11. The retainer B comprises side walls 12—12, each having an overhanging flange indicated at 13, and integrally formed curved end walls 14—14, the end walls being provided with outwardly extending securing lugs 15—15, which are secured to the base plate 10 by rivets 16—16. The securing lugs 15—15, and portions of the side and end walls 12—12, are provided with extensions 17—17 at each side of the retainer, which project downwardly over the side surfaces of the base plate A when the retainer is secured in position thereon.

Mounted in the retainer B is a bearing plate 18 which rests upon the base plate A.

Disposed in the retainer B are the anti-friction means which comprise a pair of similar rollers, each of which is provided with an axially disposed socket 20 in each end. Mounted at each side of the retainer are connecting bars 21—21, each being disposed in the off-set 19 in the side wall of the retainer beneath the overhanging flange 13. Each of the bars 21 is provided with cylindrical projections 22—22, one of the projections being arranged adjacent one end of the bar and adapted to extend into the socket 20 of one roller, while the other projection on said bar is adjacent the opposite end thereof and extends into the socket 20 of the other roller. The connecting bars 21—21 serve to connect the rollers in spaced relation for movement in unison when the

same are engaged by the body bolster of the car. A fender 23 is provided which has flanges 24—24 resting upon the rollers, the fender being attenuated in cross section intermediate its top and bottom portions so as to be disposed between the rollers as shown, the lower extremity 25 of the fender being provided with lateral extensions 26—26 which project beneath the connecting bars 21—21. The fender 23 closes the space between the rollers and prevents the entrance of foreign matter beneath the rollers at this point.

The centering means D as shown in Figures 2 and 3 is mounted in a central position with reference to the retainer, and at a point beneath the anti-friction elements C. The centering means comprises a coiled spring 27 mounted in a socket 28 formed in the base plate A, and extending upwardly through an opening 29 in the bearing plate 18. Co-operating with the spring 27 is a follower 30 having a socket 31 for the reception of the upper end of the spring 27, said follower being slidably mounted in the socket 28 of the base plate A, and in the opening 29 in the bearing plate 18, the walls of said socket and opening providing a guide for the follower to effect operative movement thereof in a vertical direction. The engaging end or head of the follower 30 is spherical in form, and is projected upwardly by the spring 27 into engagement with both of the rollers forming the anti-friction means, so as to retain the same in central position.

In operation, assuming the rollers are moved toward the right as indicated in dotted lines in Figure 1, the left-hand roller 40 passes over the follower 30 and depresses the same against the resistance offered by the spring 27, movement of the rollers in the right-hand direction being limited by engagement of the right-hand rollers with the 45 adjacent end wall of the housing which positions the spherical head of the follower 30 beneath and slightly to one side of the center of gravity of the left-hand roller, whereby upon removal of load from the 50 rollers, upward movement of the follower 30 under the influence of the spring exerts an upward thrust upon the left-hand roller slightly to one side of the center of gravity thereof, and by reason of the spherical formation of the head of the follower, the 55 thrust is not only upward in a vertical direction, but toward the left, resulting in the pair of rollers being moved toward their original starting positions, until the right-hand roller again comes into engagement 60 with the follower, which then acts to maintain the two rollers in central position. Movement of the rollers in a left-hand direction brings about operation the reverse of 65 that just described.

In assembling the bearing, the spring fol-
lower, bearing plate, rollers, fender, and
connecting bars are inserted into the retainer
B through the open bottom thereof, after
which the retainer is secured to the base
plate A as heretofore described, attention
being called to the fact that all parts are
maintained in position by the flanges 13—13
on the retainer which prevent withdrawal
of the bars 21—21, the latter in turn holding
the rollers and fender in position, and
the rollers operating to maintain the bearing
plate, and the centering means in proper
operative positions.

While I have herein shown and described
what I consider the preferred manner of
carrying out the invention, the same is merely
illustrative, and I contemplate all changes
and modifications which come within the
scope of the claims appended hereto.

I claim:

1. In an anti-friction bearing, the combination with a retainer having a bearing surface; of anti-friction means comprising a pair of rollers connected together in spaced relation for movement in unison; and yieldable means disposed beneath said rollers and extending upwardly between the same to maintain them in centered position with reference to said retainer, movement of said rollers to one side or the other of central position causing engagement thereof with said yieldable means to depress the same, said retainer being provided with means for limiting movement of said rollers to dispose the center of gravity of the roller in engagement with said means slightly to one side of the latter in a direction away from the other roller, whereby said yieldable means exert an upward thrust upon said roller to return the rollers toward centered position.

2. In an anti-friction bearing, the combination with a retainer having a bearing surface; of anti-friction means comprising a pair of rollers connected together in spaced relation for movement in unison; and yieldable means disposed beneath said rollers and extending upwardly between the same to maintain them in centered position with reference to said retainer, movement of said rollers to one side or the other of central position causing engagement thereof with said yieldable means to depress the same, said retainer being provided with means for limiting movement of said rollers to dispose the center of gravity of the roller in engagement with said means slightly to one side of the latter in a direction away from the other roller, whereby said yieldable means exert an upward thrust upon said roller to return the same toward centered position, said yieldable means including a follower having a spherical head disposed to engage said rollers, and being

urged upwardly in a vertical direction by resilient means mounted in said retainer.

3. In an anti-friction bearing, the combination with a retainer comprising a bearing plate, and side and end walls; of a pair of anti-friction elements disposed in said retainer and adapted to have rolling engagement with said bearing plate, said elements being connected in spaced relation for movement in unison; and yieldable centering means mounted in said retainer and extending upwardly beneath said elements to a position between them so as to bear upon the same, said means being limited to movement substantially at right angles to the plane of movement of said anti-friction elements, and being compressible by said elements upon movement toward opposite ends of said retainer, movement of said anti-friction elements being limited by said retainer to prevent the center of the element in engagement with the centering means from superposed vertical coincidence with the center of said centering means.

25. 4. In an anti-friction bearing, the combination with a base member adapted to be secured to a bolster; of a retainer having off-set side walls provided with overhanging top flanges, and end walls connecting said side walls, said retainer being further provided with means for securing the same to said base member; a bearing plate disposed in said retainer and resting on said base member; a pair of rollers arranged in said retainer and having rolling engagement with said bearing plate, each of said rollers being provided with an axially disposed socket in each end; connecting bars arranged within the off-set portions of the side walls of the retainer beneath the overhanging flanges thereon, and each provided with a laterally extended projection at each end, disposed in the socket of the adjacent roller for connecting said rollers together in spaced relation; centering means arranged in the bottom of said retainer, and comprising yieldable means and a follower movable substantially in a vertical direction and extending between said rollers and into engagement therewith, to maintain the rollers in central position, said means being compressible by movement of said rollers to either end of said retainer, the operative parts of said anti-friction bearing being maintained in assembled relation when said retainer is secured to said base member.

5. In an anti-friction bearing, the combination with a base member, adapted to be secured to a truck bolster, and provided with a centrally disposed socket; of a retainer having off-set side walls provided with overhanging top flanges, and end walls connecting said side walls, said retainer being secured to said base member; a bearing plate disposed in said retainer and pro-

vided with an aperture registering with the socket in said base member; a pair of anti-friction elements arranged in said retainer and having rolling engagement with said bearing plate, each of said elements being provided with a socket in each end; connecting bars arranged within the off-set portions of the side walls of the retainer beneath the overhanging flanges thereof, and each bar provided with projections disposed in the sockets of said anti-friction elements for connecting the latter together in spaced relation; a follower mounted beneath said anti-friction elements in the socket of said base member and opening of said bearing plate, the walls of which limit movement of the follower to a direction substantially at right angles to the direction of movement of said anti-friction elements; and resilient means interposed between the bottom of the socket in the base member and the follower so as to urge the latter upwardly between and into engagement with the anti-friction elements.

6. In an anti-friction bearing, the combination with a retainer having a bearing surface; of anti-friction means comprising a pair of rollers connected together in spaced relation for movement in unison; and yieldable means co-operating with said retainer and supported thereby for movement in a direction toward said rollers, substantially at right angles to the movement of said rollers back and forth in said retainer, said means extending between said rollers and bearing thereon, and being adapted to be flexed upon movement of said rollers to either side of central position, said retainer being provided with means for limiting movement of said rollers to dispose the center of the roller in engagement with said means slightly to one side of the latter, in a direction away from the other roller, whereby said yieldable means exert a thrust upon said roller to return the same toward central position.

7. In an anti-friction bearing of the character described, the combination with a pair of rollers connected together in spaced relation; of means for maintaining said rollers in central position when free from load, said means including a member confined to movement substantially at right angles to the movement of said rollers, and projecting between said rollers, and said member being yieldably urged into engagement with both of said rollers.

8. In an anti-friction bearing, the combination with a support provided with a bearing surface; of an anti-friction means having rolling engagement with said first-named bearing surface; centering means for the anti-friction means yieldingly projected above said first named bearing surface and having a curved engaging portion over

which said anti-friction means is adapted to travel; means for guiding said centering means in a vertical path; and spring means yieldingly opposing depression of said centering means, said centering means engaging said anti-friction means in a plane above the bearing surface of the support in all positions of the traveling movement of said anti-friction means.
